(57) CLAIM

We claim the ornamental design for a cooler having detachable legs, as shown and described.

DESCRIPTION

FIG. 1 is a perspective view of the cooler having angular legs attached thereto.

FIG. 2 is a perspective view of the cooler having square legs attached thereto.

FIG. 3 is a perspective view of the cooler having round legs attached thereto.

FIG. 4 is a left side view of the cooler having the legs removed therefrom.

FIG. 5 is a right side view of the cooler having the legs removed therefrom.

FIG. 6 is a bottom view of the cooler having slots for the attachment of angular legs thereto.

FIG. 7 is a bottom view of the cooler having slots for the attachment of square legs thereto.

FIG. 8 is a bottom view of the cooler having slots for the attachment of round legs thereto.

FIG. 9 is a front view of the cooler having the legs removed therefrom.

FIG. 10 is a back view of the cooler having the legs removed therefrom.

FIG. 11 is a back view of the cooler showing the legs in the stored position.

FIG. 12 is a left side view of the cooler showing the legs in the stored position; and,

FIG. 13 is a top view of the cooler showing the legs in the stored position.
